CAN RESEALER OR THE LIKE

Asa P. Ruskin, 865 West End Ave.,
New York, N.Y. 10025

Filed Dec. 27, 1971, Ser. No. 212,847

Term of patent 14 years

Int. Cl. D9—07

U.S. Cl. D9—282

FIG. 1

FIG. 2

FIG. 4

FIG. 3

FIG. 5

FIG. 6

FIG. 1 is a front elevational view of a can resealer or the like showing my new design;

FIG. 2 is a top plan view thereof;

FIG. 3 is a bottom plan view thereof;

FIG. 4 is a left end elevational view thereof;

FIG. 5 is a right end elevational view thereof; and,

FIG. 6 is an enlarged cross sectional view thereof, taken along the plane of line 6—6 in FIG. 1.

I claim:

The ornamental design for a can resealer or the like, as shown.
